EDWIN R. GILL, OF YONKERS, NEW YORK, ASSIGNOR, BY MESNE ASSIGNMENTS, TO HALL SWITCH & SIGNAL COMPANY, A CORPORATION OF MAINE.

SELECTIVE SIGNALING APPARATUS.

1,137,474.

Specification of Letters Patent. Patented Apr. 27, 1915.

Application filed October 21, 1910. Serial No. 588,359.

To all whom it may concern:

Be it known that I, EDWIN R. GILL, residing at Yonkers, in the county of Westchester and State of New York, have invented certain new and useful Improvements in Selective Signaling Apparatus, of which the following is a specification.

This invention relates to what are known as "high speed" selectors for telephones, telegraphs, and the like. Such selectors have heretofore been contrived, whereby a number of signals at different points may be selectively operated by electrical impulses over a single wire without interference among themselves, the several selectors being controlled as by an automatic sender, wherein a movable contact is impelled forward rapidly step-by-step, the mechanism being so arranged that pauses may be produced after any one step forward, so that each pause will cause a selector to operate at a different and only one station. By pausing after the appropriate forward step, the operator is able to cause the operation of the selector at whichever station he pleases, thus to call that station without disturbing any other upon the line. The selectors used in connection with such selective signaling are known as "high speed" selectors, and an example, and upon which the present invention is an improvement, is shown in my co-pending application Serial No. 451,662, filed September 4th, 1908, patented October 3, 1911, No. 1,004,566. In the use of such selectors, there is one selector for each station to be called, and any one or succession may be caused to operate, as the operator makes a pause after one or a succession of actuating impulses. The difficulty has been that the selectors could not be returned to normal, save by stepping them up through their appointed movement. Accordingly, if the first selector, for instance, of a series were operated, in order to bring all the instruments to normal, the actuating impulses would have to be continued until all, even the very last, of the selectors had completed their appointed phase and been *de facto* returned to the normal condition necessary to proper operation.

The present invention, therefore, contemplates a change in the construction of selectors of the kind referred to whereby upon a break in the line, such as is caused when

the despatcher has sent out all the actuating impulses necessary to call the station or stations desired, all the selectors will automatically return to normal, regardless of whether or not their operative phase has been completed.

The invention consists of the elements, combinations, arrangements of parts and applications of principles, all as will be hereinafter fully set forth; and the scope of protection contemplated will be indicated in the claims.

In the accompanying drawings, which are to be taken as a part of this application, and in which I show a merely preferred form of embodiment of the invention; Figure 1 is a sectional view of a selector embodying my invention, showing certain of the parts in elevation; Figs. 2 and 3 are perspective views of details; Fig. 4 is an end elevation of the selector with the casing removed; Fig. 5 is a top plan view of the same, partly broken away; Fig. 6 is a side elevation, looking at one side of the selector; Fig. 7 is a similar view looking at the other side of the selector; and Fig. 8 is a perspective of one of the timing devices.

Referring to the numerals on the drawings, 1 indicates a casing, inclosing a frame work 2 that supports a horizontal shaft 4, upon which is carried a ratchet wheel 5 that is normally impelled in the direction of the arrow in Fig. 1 by the spiral spring 6 and which may be termed a control wheel for the mechanism. An electro-magnet 7 acts through armature 8, bowed spring 9 and connecting rod 10 to operate an impelling lever 11. An impelling pawl 12 is pivoted to the end of the lever 11, and is provided with an arm 14 against which bears the spring 15. The function of this spring is to direct the lower end of the pawl into the successive teeth on the wheel 5. A stop 16 is provided to limit the downward movement of pawl 12. Whenever energization of the magnet permits the lever 11 to move downward on its pivot 17, the impelling pawl 12 will engage the ratchet wheel 5, and move the same one tooth forward. When the electro-magnet 7 is de-energized, the spring 9 causes the lever 11, and with it the pawl 12, to rise. When this motion takes place a retaining pawl 18 on a pivoted arm 19, acts on the teeth of the ratchet 5 to pre-

vent return to normal under the influence of spring 6 (see Figs. 5 and 6).

For reasons explained hereinafter, the arm 19 is carried on a shaft 20, rotatable in opposite side pieces of the frame, and movable upon the long journals shown in Fig. 4, whereby the pawl 18 may be disengaged from the wheel 5 upon longitudinal movement of the shaft 20. The inclination of the shaft 20 facilitates return of the pawl 18 into engagement with the wheel 5 as hereinafter described, and also tends to keep the pawl always over the wheel when it is intended that it shall be there. It is desirable that the action of the wheel 5 and its driving parts should be substantially as follows: When the wheel is at normal, and before any call is begun, any rapid impulses should produce only a back and forth motion through the space of one tooth. When a call is to be begun, a pause during an impulse (the magnet 7 being energized) should prepare the wheel for action, and thereafter every impulse, whether including a pause or not, should cause the wheel to move forward one step without backward movement, until the phase of movement of the wheel has been completed. Fig. 2 shows the normal position of the wheel 5 and lever 19. In this position the lever 19 is supported in an elevated position with the pawl 18 out of engagement with the wheel, a catch 21 on the lever 19 being held over a hook 22 which is fixed to a rock-shaft 23 (see Fig. 1). This relation between the catch 21 and the hook 22 is permitted because a tail-piece 24 of the hook 22 bears on a flattened part 25 of the hub 26, fixed to the shaft 4 (Figs. 1 and 2).

The movement of the wheel 5 the distance of one tooth removes the member 37 from the end of the lever 19 and permits the part 21 to engage the hook 22 but does not cause sufficient movement of the hook 22 to liberate the lever 19 and drop the pawl 18 upon the wheel 5, and therefore any number of quick movements of the impelling pawl 12 merely produces quick back and forth movement of the wheel 5. In order to cause the wheel 5 to progress through its whole intended course, means are provided whereby a pause of sufficient duration, occurring while the pawl 12 is depressed, causes the pawl 18 to be dropped upon the wheel into position to hold the same during upward movement of the impelling pawl 12. For this purpose I prefer to employ the following means: Upon a shaft 27 which is suitably journaled in the frame 2 (Fig. 5) is fixed a lever 28 (Figs. 7 and 8) to the outer extremity of which is pivoted a frame work 29 carrying an inertia wheel 30, the hub 31 whereof rests upon an inclined track 32 and is adapted to slide or roll thereon. This wheel is held near the upper end of the track 32 by the arm 34, fixed on the lever

11 (Figs. 1 and 7.) Thus each time the impelling pawl 12 is depressed, the wheel 30 begins to roll slowly down the track 32, and whenever the pawl 12 rises, the arm 34 causes the wheel to slide quickly back up the track 32. The track 32 consists of a rail or rod whose lower end is fixed in a pivoted stud 32' and whose upper end is fixed within a movable stud 32'', the latter extending through a vertical slot formed in the frame 2 and being provided on the opposite face of the side of the frame with a set screw. This permits the adjustment of the track 32 for the purpose of regulating the rate of movement of the wheel 30 (Fig. 7). If the impelling pawl 12 be depressed long enough, the wheel 30 will roll down far enough to permit the frame work 29 to contact a lever 35, fixed to the revoluble shaft 23, (Figs. 1 and 7) to which the hook 22 is fixed. This action pushes the hook 22 away from under the catch 21, thus releasing the pawl 18, and permitting it to fall upon the wheel 5. After this, as the wheel progresses step-by-step under the influence of the impelling pawl 12, the catch 21 does not at any time rise high enough to rest upon the hook 22, which moreover is held out of engaging position by the engagement of the rounded portion of hub 26 with the hook extension 24. It follows therefore that whether the forward impulses follow each other quickly or with intermediate pauses, the wheel 5 will move forward until an inclined tooth 36 (Figs. 1 and 2) of the wheel 5 comes in contact with the pawl 18. The function of this inclined tooth 36 is to cause the lever 19 and its pawl 18 to move laterally so as to release the wheel 5. The spring 6 (see Fig. 4) at once returns the wheel to normal, at the end of which return movement an inclined pin 37 (Figs. 1 and 2) on the wheel 5 acting upon the inclined forward face of lever 19 raises the catch 21 above the hook 22, this being possible because the hook extension 24 is now resting against the flat face of hub 26, and the hook may therefore swing beneath catch 21. The inclined pin 37 on the wheel also causes return longitudinal movement of the shaft 20, whereby the pawl 18 is brought back into the plane of the wheel 5. It will thus be seen that by beginning with a long impulse followed by either long or short impulses, the wheel 5 may be progressed any predetermined number of teeth.

An illustrative object of the entire device is to cause the closing of a normally opened circuit, and this end is attained as follows: A spring contact arm 38 is secured to an insulating block 39 (Fig. 1) that is adjustably fixed to the rock shaft 27, whose movements, as will be understood, are governed by those of the wheel 30. This spring terminal is connected by a fine flexible conne-

tion 40 to an arm 41, held upon and insulated from the machine frame, and connected by wire 42 (Fig. 6) to the binding post 44. The machine frame is connected to binding post 45, and there is a contact arm 46 (Figs. 1, 4 and 5) fixed upon the shaft 4 and moving in the plane of the spring contact 38. The contact 46 is adjustably held on shaft 4, and by this adjustment any given instrument may be arranged for operation by any desired proper combination of impulses within its scope. As the wheel 5 is revolved, the contact arm 46 will be brought directly beneath the spring contact 38, and contact 15 between the two members will be effected, if at this point a pause is made after the impulse, so that the inertia wheel 30 will have an opportunity to roll down its track 32 and cause the shaft 27 of the spring contact 20 to rock; contact, of course, continuing only so long as pawl 12 remains depressed.

Referring to Figs. 1, 3, 4, and 5, the numeral 47 indicates an inertia device to prevent undesirable rebound of wheel 5. This 25 takes the form of a weight, frictionally attached to shaft 4, extending across the same and pressed against it by wire 48, so as to produce the proper amount of friction.

The construction and operation of the device thus far described are similar to those of the device described in my copending application already referred to, but aside from minor differences between that invention and the present one, it is to be noted that I 30 have provided another timing element, whose function is to return the wheel 5 to normal automatically in a case where the wheel has not been progressed sufficiently to bring its inclined tooth 36 into action, upon 35 the happening of a break in the line of predetermined extent. To this end I have provided upon the opposite side of the frame from that occupied by the inertia wheel 30, a second inertia wheel 49, (Figs. 4, 5 and 45 6) which controls means for returning the wheel 5 to normal as stated. This timing element comprises an arm 50, fixed to a shaft 51 held at the side of the machine frame, and to the outer end of which is pivoted a 50 frame work 52, carrying a hub 54 and wheel 49, similar to those already described upon the opposite side of the machine. The hub 54 runs upon a track 56 the inclination of which to the horizontal is opposite to that 55 of the track 32. The wheel 49 is adapted to be slid up its track by means of an arm 57 which is secured to the forward end of the lever 11, so that upon each downward movement of the impelling pawl 12, the inertia wheel 49 is slid up its track. When the 60 impelling pawl 12 rises upon deenergization of the magnet 7, the inertia wheel 49 will begin to roll slowly down its track, and if this movement is allowed to continue for a sufficient time, the ratchet wheel 5 will be re-

leased from any engagement which it may have with the pawl 18, in the following manner:

Referring to Figs. 1 and 5 a piece 58 is loosely mounted upon two pins 59 and 60, 70 secured in the machine frame, so that it may have considerable lateral movement, this movement being preferably limited by collars 70 and 71 on the pins between which it plays. The said piece 58 has a finger 61 75 which is in line with the arm 19, when the pawl 18 of the latter is resting upon the wheel 5. Said piece 58 also has a part 62, which extends between member 65 and one side of the frame work 52. When, upon 80 depression of the pawl 12, the wheel is moved up its track, part 62 of piece 58 is engaged by the member 65 of the frame work 52, and the piece 58 is moved on its bearings in such a way as to draw the finger 61 away from the arm 19. When there is a break in the line for a certain time, that is to say, when, after the pawl 12 has been allowed to rise and there is no succeeding downward movement of the pawl 12 for a 90 certain period, the inertia wheel 49 will be free to roll down its track, and as it does so the part 62 of piece 58 is engaged by the frame work 52, which causes the finger 61 to move toward and engage the arm 19 if 95 the pawl 18 is in engagement with the wheel 5, moving the shaft 20 laterally on its long journals and thereby disengaging the pawl 18 from the wheel, which thereupon is returned to normal by its spring 6.

The operation of my selectors, whereby a circuit is closed at a selected station exclusively is as follows: Supposing the group of stations upon a single line to be twenty-four, then one of my instruments is placed 105 at each station, and the contact arms 46 on the different shafts 4 are separately adjusted to twenty-four different positions. Instrument number one will be arranged so that movement of the wheel 5 by one tooth 110 beyond the starting position will bring its contact arm 46 directly under the tip of its contact arm 38. Instrument number two will be arranged to reach this position after two forward impulses of the wheel; and so 115 on with the other twenty-two in succession. All of the instruments will be arranged in a well known manner, so that their magnets 7 are all energized simultaneously by any make and break upon the common line wire. 120 Supposing now that station number 6 is to be exclusively actuated. The instruments being all in the normal position (through the operation of the timing element 49), the operator will first hold circuit through all 125 the magnets 7 closed long enough to permit the timing element 30 to release catches 21 from hooks 22, so that pawls 18 may engage the first teeth on wheels 5. Six impulses will now be produced, of which the first five 130

may be long or short, but the last must be long enough to give the contact arm 38 time to descend. These six impulses will have brought the contact arm 46 at instrument 5 number six directly under the contact arm 38, while the contact arms 46 in all the other instruments will have moved either too far or not far enough. Consequently, although the contact arms 38 in all the grouped instruments 10 will descend simultaneously during the last pause, only that at station six will descend upon its corresponding contact arm 46. A local circuit will thus be controlled at station number six only.

15 Any or all of the selectors on a line may thus be actuated in rapid succession. It is only necessary to produce, say twenty-four energizations of all the magnets in succession, pausing at the proper intervals corresponding 20 to the stations wanted, whereby local signals may be produced in such stations as are selected, in rapid succession, and without disturbing others. Obviously, to perform such an operation, it is necessary that 25 all instruments should start from normal. Without the second timing element which I have provided, supposing that station one only had been called, the other twenty-three instruments would be held stepped up to the extent of one tooth, and to bring them to normal, they would all have to complete their phase of movement. That is, twenty-three more impulses would have to be produced. With my restoring device 30 the instruments of a group are all automatically returned to normal when the sending of impulses ceases for a given length of time.

As many changes could be made in the above construction and many apparently 40 widely different embodiments of this invention could be made without departing from the scope thereof, it is intended that all matter contained in the above description or shown in the accompanying drawing shall 45 be interpreted as illustrative and not in a limiting sense.

It is also to be understood that the language used in the following claims is intended to cover all of the generic and specific 50 features of the invention herein described and all statements of the scope of the invention, which as a matter of language, might be said to fall therebetween.

Having thus described my invention, what 55 I claim as new and desire to secure by Letters Patent, is:

1. In a device of the kind described, a control wheel adapted to be moved in a step-by-step rotation, means tending to retain 60 said control wheel in a normal position, means actuated by a series of impulses and engaging said control wheel to impart a step-by-step rotation thereto against the action of said retaining means, and a time element 65 whose function it is to render said ac-

tuating means inoperative for rotating said control wheel until a long impulse has been impressed upon the line of sufficient duration to permit said time element to perform its function; all in combination with means 70 for releasing said control wheel whereby said control wheel may be restored to normal position by said first mentioned means after any degree of rotation.

2. In a device of the kind described, a 75 control member adapted to be stepped through a phase of movement, means for stepping said control member, means opposing the stepping of said control member, means coöperating to free said control member from the action of said stepping means after said control member has been rotated through its full phase of movement, and a time element coöperating to free said control member and permit its return to 80 normal position under the influence of said opposing means after the completion of any movement of said control member in the event of the failure of said first mentioned freeing means to operate.

3. In a device of the kind described, a toothed control member adapted to be stepped by one long and a series of short impulses, means tending to return said control member to normal position, a pawl 95 adapted to engage the teeth of said control member to prevent such return movement, a time controlled mechanism adapted to bring the control member and the pawl into operative relation, and a second time controlled mechanism adapted to throw said pawl out of operative relation with said control member, said last mentioned time controlled mechanism being normally inoperative against said pawl.

4. In a device of the kind described, a toothed control member adapted to be stepped by one long and a series of short impulses, means tending to return said control member to normal position, a pawl 100 adapted to engage the teeth of said control member to prevent such return movement, means whose operation is determined by said long impulse for bringing the pawl and the control member into operative relation, and means whose operation is affected by a determined length of pause between impulses for throwing the pawl and the control member out of operative relation.

5. In a device of the kind described, a 110 toothed control member adapted to be stepped by a long and a series of short impulses, means tending to return said control member to normal position, a pawl 115 adapted to engage the teeth of said control member to prevent such return movement, a time element whose operation is determined by said long impulse for bringing about operative relation between the control member and the pawl, and means whose 120

105

110

115

120

125

130

operation is affected by a determined length of pause between impulses for throwing the pawl and the control member out of operative relation.

6. In a device of the kind described, a toothed control member adapted to be stepped, means tending to return said control member to normal position, a pawl adapted to engage the teeth of said control member to prevent such return movement, a time element whose operation is determined by an impulse of longer duration than the impulses for successively stepping said member adapted for bringing about operative relation between the control member and the pawl, and a time element whose operation is determined by a pause of a greater length than the pauses between said stepping impulses for throwing the pawl and control member out of operative relation.

7. In a device of the kind described, a toothed control member adapted to be stepped, means tending to return said control member to normal position, a pawl adapted to engage the teeth of said control member to prevent such return movement, a time element whose operation is determined by an impulse of longer duration than the impulses for successively stepping said member adapted for bringing about operative relation between the control member and the pawl, means whose operation is determined by a relatively lengthened pause between impulses adapted for throwing said pawl out of operative relation with said control member when said control member has completed its phase of movement.

8. In a device of the kind described, a control wheel adapted to be moved in a step by step rotation, means tending to retain said control wheel in a normal position, means actuated by a series of impulses and engaging said control wheel to impart a step by step rotation thereto against the action of said retaining means; and a time element whose function it is to render said actuating means inoperative for rotating said control wheel, except after a long impulse has first been impressed upon the line; all in combination with a second time controlled means whose function it is to release said control wheel, whereby it may be restored to normal position by said first mentioned means whenever a pause occurs in the line of sufficient duration to permit said second time controlled means to perform its function.

9. In a device of the class described; a circuit closer comprising a member adapted to be moved into circuit closing position by a series of impulses, means tending to return said circuit closing member to normal position, retaining means adapted to retain said circuit closing member against such return movement, time controlled mechanism for

effecting operative relation between said circuit closing member and said retaining means only after a predetermined length of time; and a second time controlled member adapted to move said retaining means out of operative relation with said circuit closing member.

10. In a device of the kind described, a toothed wheel adapted to be stepped and having a hub provided with a flattened portion, means tending to return said wheel to normal position, a pawl adapted to engage the teeth of said wheel to resist such return movement movable toward said wheel along two planes, and means engaging the flattened portion of said hub whereby to retain said pawl against movement along one of said planes.

11. In a device of the kind described, a toothed member adapted to be stepped, means opposing the stepping of said member, a pawl adapted to engage the teeth of said member and prevent operation of said opposing means, and a hook adapted to support said pawl out of engagement with the teeth of said member, a time element for throwing the pawl out of engagement with the hook and into engagement with the teeth, and a time element for throwing the pawl out of engagement with the teeth.

12. In a device of the kind described, a toothed wheel adapted to be stepped, means opposing said stepping movement, a pawl movable toward and from the wheel in two planes, a hook adapted to hold the pawl away from the wheel in one of its planes of movement, an oscillatory member adapted to engage the pawl and move it in its other plane of movement, and a time element for actuating said oscillatory member.

13. In a device of the kind described, a toothed wheel adapted to be stepped and having a hub provided with a flattened portion, means opposing the stepping of said wheel, a pawl movable toward and from the wheel in two planes of movement, a hook adapted to hold the pawl away from the wheel in one of its planes of movement, an extension on said hook resting upon the flattened portion of said hub, an oscillatory member adapted to engage the pawl and move it away from the wheel in a parallel plane of movement, and a movable element adapted to ride into engagement with said oscillatory member and swing the latter.

14. In a device of the kind described, a toothed wheel adapted to be stepped and having a hub provided with a flattened portion, means tending to return said wheel to normal position, a pawl adapted to engage the teeth of said wheel to resist such return movement movable toward said wheel along two planes, means engaging the flattened portion of said hub whereby to retain said pawl against movement along one of said planes.

planes, and said hub being adapted to hold said last mentioned means out of retaining relation with said pawl while the wheel is being stepped.

- 5 15. In a device of the kind described, a toothed wheel adapted to be stepped and having a hub provided with a flattened portion, means tending to return said wheel to normal position, a pawl adapted to engage 70
10 the teeth of said wheel to resist such return movement movable toward said wheel along two planes, and a pivotally mounted hook having a part engaging the flattened portion of said hub whereby to retain said pawl 75
15 against movement along one of said planes.

16. In a device of the kind described, a toothed wheel adapted to be stepped and having a hub provided with a flattened portion, means tending to return said wheel to 80
20 normal position, a pawl adapted to engage the teeth of said wheel to resist such return movement, and means normally engaging the flattened portion of said hub whereby 85
25 to retain said pawl out of coöperative relation with said wheel.

17. In a device of the kind described, a toothed wheel adapted to be stepped and having a hub provided with a flattened portion, means tending to return said wheel to 90
30 normal position, a pawl adapted to engage the teeth of said wheel to resist such return movement, means normally engaging the flattened portion of said hub whereby 95
35 to retain said pawl out of coöperative relation with said wheel, and said hub being adapted to hold said last mentioned means out of retaining relation with said pawl 100
40 while the wheel is being stepped.

18. In a device of the kind described, a toothed wheel adapted to be stepped and having a hub provided with a flattened portion, means tending to return said wheel to normal position, a pawl adapted to engage 105
45 the teeth of said wheel to resist such return movement, and movable toward said wheel along two planes, and two time controlled means operating independently of each other one for influencing the movements of 110
50 said pawl in each of its planes of movement, one of said time controlled means depending 115
55 for its effectiveness upon the position of the flattened portion of said hub.

19. In a device of the kind described, a toothed wheel adapted to be stepped and having a hub provided with a flattened portion, means tending to return said wheel to normal position, a pawl adapted to engage the teeth of said wheel to resist such return movement movable toward said wheel along 120
60 two planes, and means engaging the flattened portion of said hub whereby to retain said pawl against movement along one of said planes, and independent means adapted to move the pawl toward the wheel along its other plane of movement.

20. In a device of the kind described, a toothed wheel adapted to be stepped and having a hub provided with a flattened portion, means tending to return said wheel to normal position, a pawl adapted to engage the teeth of said wheel to resist such return movement movable toward said wheel along two planes, and means engaging the flattened portion of said hub whereby to retain said pawl against movement along one of said planes, and independent means adapted to engage the pawl to move it away from the wheel along its other plane of movement.

21. In a device of the kind described, a toothed wheel adapted to be stepped and having a hub provided with a flattened portion, means tending to return said wheel to normal position, a pawl adapted to engage the teeth of said wheel to resist such return movement movable toward said wheel along two planes, and means engaging the flattened portion of said hub whereby to retain said pawl against movement along one of said planes, means adapted to move the pawl toward the wheel along its other plane of movement, and independent means operating to move the pawl away from the wheel along its last mentioned plane of movement.

22. In a device of the kind described, a toothed wheel adapted to be stepped and having a hub provided with a flattened portion, means tending to return said wheel to normal position, a pawl adapted to engage the teeth of said wheel to resist such return movement movable toward said wheel along two planes, and means engaging the flattened portion of said hub whereby to retain said pawl against movement along one of said planes, and time controlled means adapted to engage the pawl to move it away from the wheel along its other plane of movement.

23. In a device of the kind described, a toothed wheel adapted to be stepped and having a hub provided with a flattened portion, means tending to return said wheel to normal position, a pawl adapted to engage the teeth of said wheel to resist such return movement movable toward said wheel along two planes, means engaging the flattened portion of said hub whereby to retain said pawl against movement along one of said planes, means adapted to move the pawl toward the wheel along its other plane of movement, and time controlled means operating to move the pawl away from the wheel along its last mentioned plane of movement.

24. In a device of the class described, a control wheel adapted to be rotated in a step by step movement, means tending to retain said control wheel in a normal position, means for stepping said control wheel against the action of said retaining means, a pawl adapted to prevent operation of said 130

retaining means, a retaining member adapted to normally hold said pawl out of engaging relation with said wheel, and means movable with said wheel adapted to engage

5 said retaining member to hold it out of retaining relation with the pawl after the wheel has been rotated a notable distance.

25. In a device of the class described, a control wheel adapted to be rotated in a step

10 by step movement, means tending to retain said control wheel in a normal position, means for stepping said control wheel against the action of said restraining means, a pawl adapted to prevent operation of said

15 retaining means, a retaining member adapted to normally hold said pawl out of engaging relation with said wheel, time controlled means for removing said retaining member out of retaining relation with the pawl, and

20 means movable with said wheel adapted to engage said retaining member to hold it out of retaining relation with the pawl after said time controlled means has performed its function and the wheel has been rotated

25 a notable distance.

26. In a device of the class described, a rotatably mounted contact point adapted to be rotated into a predetermined position, a second contact point adapted to be moved

30 into engagement with said first contact point, and independently operating time controlled mechanisms, one governing the movements of each of said contact points.

27. In a device of the class described, a rotatably mounted contact point adapted to be rotated into a predetermined position, a second contact point adapted to be moved

35 into engagement with said first contact point, a plurality of independently operating time controlled mechanisms for govern-

ing the movements of said first contact point, and one of said time controlled mechanisms being adapted also to govern the movements of said second contact point.

28. In a device of the kind described, a member adapted to be stepped through a phase of movement by a series of impulses, means normally opposing the rotation of said member, means for retaining said member against the action of said opposing means, automatically operating means for releasing said member from the action of said retaining means when the member has been stepped through its phase of movement, and a second means automatically operative for releasing said member before the latter has finished its normal phase of movement.

29. In a device of the kind described, a member adapted to be stepped through a phase of movement by a series of impulses, means opposing the stepping of said member, means whose operation is determined by an impulse of predetermined length adapted to render said opposing means inoperative, means on said member for automatically restoring said opposing means to operative condition when the said member has been stepped through its phase of movement, and a second means controlled for automatically restoring said opposing means to operative condition when the member has not been stepped through its full phase of movement.

In testimony whereof I affix my signature in the presence of two witnesses.

EDWIN R. GILL.
